The ornamental design for an operating panel for an electronic percussion instrument, as shown and described.

DESCRIPTION

FIG. 1 is a right side view showing our design.

FIG. 2 is a top view thereof.

FIG. 3 is a top front/right-side view thereof, rotated approximately 45° about the horizontal axis and approximately 30° about the vertical axis with respect to FIG. 2.

FIG. 4 is a front view thereof.

FIG. 5 is a back view thereof; and,

FIG. 6 is a left side view thereof.

The broken lines shown in the drawings are to illustrate environment only and form no part of the claimed design.
